(57) **CLAIM**

The ornamental design for a timer, as shown and described.

DESCRIPTION

FIG. 1 is an elevated front perspective view of a timer, according to our new design;

FIG. 2 is an elevated rear perspective view of the timer shown in FIG. 1;

FIG. 3 is a front view of the timer shown in FIG. 1;

FIG. 4 is a rear view of the timer shown in FIG. 1;

FIG. 5 is a top view of the timer shown in FIG. 1;

FIG. 6 is a bottom view of the timer shown in FIG. 1;

FIG. 7 is a first side view of the timer shown in FIG. 1;

FIG. 8 is a second side view of the timer shown in FIG. 1;

FIG. 9 is a front view of the timer shown in FIG. 1 in a first alternative position;

FIG. 10 is a front view of the timer shown in FIG. 1 in a second alternative position;

FIG. 11 is a front view of the timer shown in FIG. 1 in a third alternative position;

FIG. 12 is a front view of the timer shown in FIG. 1 in a fourth alternative position; and,

FIG. 13 is a front view of the timer shown in FIG. 1 in a fifth alternative position.

The portions of the figures shown in broken lines are unclaimed. Any empty region surrounded by broken lines is also unclaimed, inclusive of the broken line itself.

1 Claim, 13 Drawing Sheets

Rain Bird Corporation, the product shown in attachment 8 was apparently sold or offered for sale at least by Mar. 19, 2012.

Orbit Irrigation Products, Inc., the product(s) shown in attachment 9 were sold or offered for sale at least by Mar. 19, 2012.

Office Action, U.S. Appl. No. 29/527,487, Mailed on May 9, 2016 (shown in attachment 10).

Office Action Response, U.S. Appl. No. 29/527,487, Dated on Aug. 9, 2016 (shown in attachment 11).

Terminal Disclaimer, U.S. Appl. No. 29/527,487, Dated on Aug. 9, 2016 (shown in attachment 12).

Office Action, U.S. Appl. No. 29/527,488, Mailed on May 10, 2016 (shown in attachment 13).

Office Action Response, U.S. Appl. No. 29/527,488, Dated on Aug. 9, 2016 (shown in attachment 14).

Terminal Disclaimer, U.S. Appl. No. 29/527,488, Dated on Aug. 10, 2016 (shown in attachment 15).

Notice of Allowance and Fee(s) Due (including a Notice of Allowability for a Design Application section, and an Examiner’s Comment section), U.S. Appl. No. 29/527,487, Mailed on Sep. 13, 2016 (shown in attachment 16).

Notice of Allowance and Fee(s) Due (including a Notice of Allowability for a Design Application section, and an Examiner’s Comment section), U.S. Appl. No. 29/527,488, Mailed on Sep. 12, 2016 (shown in attachment 17).

Preliminary Amendment, U.S. Appl. No. 14/719,277, Dated on Sep. 27, 2016 (shown in attachment 18).

Notice of Allowance and Fee(s) Due (including a Notice of Allowability section, an Allowance Response to Preliminary Amendment section, an information Disclosure Statement section, an Election/Restrictions section, an Election without Traverse section, an Examiner’s Amendment section, and an Allowable Subject Matter section), U.S. Appl. No. 14/719,277, Mailed on Oct. 7, 2016 (shown in attachment 19).

Amendment After Allowance, U.S. Appl. No. 29/527,487, Dated on Dec. 8, 2016 (shown in attachment 20).

Issue Fee Transmittal, U.S. Appl. No. 29/527,487, Dated on Dec. 9, 2016 (shown in attachment 21).

Amendment After Allowance, U.S. Appl. No. 29/527,488, Dated on Dec. 8, 2016 (shown in attachment 22).

Issue Fee Transmittal, U.S. Appl. No. 29/527,488, Dated on Dec. 9, 2016 (shown in attachment 23).

Amendment After Allowance, U.S. Appl. No. 14/719,277, Dated on Jan. 9, 2017 (shown in attachment 24).

Issue Fee Transmittal, U.S. Appl. No. 14/719,277, Dated on Jan. 9, 2017 (shown in attachment 25).
